MANICURIST'S HAND SUPPORT

Fernando Perez, Pittsburgh, Pa.

Application May 6, 1938, Serial No. 206,394

7 Claims. (Cl. 132—73)

This invention relates to a hand support for use during the operation of manicuring and has for an object to produce such a support which is comfortable and convenient for the subject and which facilitates the activities or manipulations of the manicurist.

A further object is to produce such a support which is rugged and durable but which is readily and easily adjusted to suit the convenience and comfort of the subject and also of the operator.

These and other objects which will be made more apparent throughout the further description of the invention are attained by means of apparatus illustrated in the drawings accompanying and forming a part hereof.

In the drawings, Figure 1 is a front elevation of a support embodying my invention and illustrates an adjustment of the hand rest for the purpose of bringing the thumb of the right hand of the subject to a position such as will facilitate the manicuring operations to be performed on the thumb.

Fig. 2 is a sectional view of the support, the section being taken along the line 2—2 of Fig. 3.

Fig. 3 is a rear view of the support showing the hand rest in the upright position, i. e., in the position to which it is moved preparatory to the operation of manicuring the fingers.

Fig. 4 is a side view of the support shown in association with a representation of a left hand in position for performing the manicuring operations on the index finger.

The support consists essentially of a pedestal 5, a standard 6 adjustably mounted on the pedestal, and a hand rest 7 adjustably mounted on the standard. The pedestal is of such form that it provides a base plate 8 of sufficient area that the support stands firm for all positions of the hand rest 7 and under the weight of a hand supported on the rest. As illustrated, the pedestal is provided with an upwardly extending boss 9 which is provided with a cylindrical aperture adapted to receive the lower end of the standard 6. The cylindrical aperture is, however, so formed within the boss as to provide a step bearing 10 which is engaged by the lower end of the standard 6 when the standard is in place within the aperture. The arrangement is such that the standard may be turned to different positions with relation to the boss and I have diagrammatically illustrated a latch 11 which may be pivotally secured to the boss and is adapted to engage one or another of several recesses 12 formed in the standard 6. As shown, the latch 11 is located in a recess formed in the upper edge of the boss and is pivotally se-

cured to the boss by means of a pin 13. The latch is also provided with an operating handle 14 which projects outwardly to a position convenient to the operator.

The standard 6 is substantially L-shaped and the portion thereof adapted to receive and support the hand rest 7 projects horizontally and substantially at right angles to the portion of the standard which projects into the aperture of the boss 9. The hand rest 7 is pivotally secured to the horizontally projecting end of the standard by means of a screw 14 which projects through a suitable aperture formed in a supporting flange 15 with which the hand rest 7 is provided, and which is screwed into a suitably tapped aperture formed in the end of the standard 6.

In the illustrated embodiment the standard is adapted to be held in an upright position such as illustrated in Figs. 2, 3 and 4, a lateral position such as illustrated in Fig. 1, and a lateral position corresponding to that in Fig. 1 but wherein the rest is swung to the other side of the standard. For this purpose the standard 6 is provided with a latch 16 which is adapted to separately engage each of three apertures 17 formed in the flange 15 of the hand rest and is so located as to secure the rest in the three positions above described. The latch 16 is more or less diagrammatically illustrated as in the form of a bolt which is located within a guiding slot 18 formed in the standard 6. The slot 18 is preferably so formed that it will retain the bolt-like latch in position within it but at the same time permits its ready movement to latching and unlatching positions with relation to the various apertures 17. This may be accomplished by so forming the slot that it approximates the form of the latch and the latch may be slidably secured in place within the slot by any procedure such, for example, as the partial peening over of the edges of the slot. As shown, the latch is provided with a handle 16' which projects above the slot and is easily accessible for the purpose of adjusting the position of the latch. The hand rest 7 is bilaterally symmetrical and for this reason can be used as a rest for either hand. In the illustrated embodiment it is provided with four finger-receiving grooves 20, 21, 22 and 23 arranged in a series which extends transversely across the top of the rest, as shown in Fig. 3, and two thumb-receiving grooves 24—25, one being located at each side of the rest. The drawings disclose that each finger-receiving groove is divided into three parts and therefore provides an individual rest for each articulated portion of the finger. That is to

say, each finger groove includes a part for receiving the portion of the finger located between the knuckle and the first joint, a part for receiving the portion of the finger between the first and second joints and a part for receiving the tip of the finger. The separate parts of each groove are aligned but extend at an angle to each other and their relative positions are such as to accommodate the natural position of the hand when the 10 muscles of the fingers are relaxed. As shown in Figs. 1, 3 and 4, the finger groove made up of the parts designated by the reference characters 20, 20' and 20'' is so placed that it accommodates the index finger of the left hand or the little finger 15 of the right hand. The groove made up of the parts indicated by the reference characters 21, 21' and 21'' is adapted to receive the middle finger of the left hand or the ring finger of the right hand. The groove made up of the parts 20 designated by the reference characters 22, 22' and 22'' is adapted to receive the ring finger of the left hand or the middle finger of the right hand and the groove made up of the parts designated by the reference characters 23, 23' and 23'' 25 is adapted to receive the little finger of the left hand and the index finger of the right hand.

The thumb grooves are also hollowed out to more or less fit the contour of the portion of the thumb engaged by them and each is formed 30 in two parts. For example, Figs. 1 and 3 disclose that each thumb groove is made up of two parts, i. e., those parts designated by the numeral 24 or 25 which are adapted to receive the portion of the thumb between the knuckle and the joint 35 of the thumb, and those parts designated by the reference characters 24' or 25' which are adapted to receive the tip portion of the thumb. It will be understood that the parts designated 24—24' constitute the thumb groove for the 40 right-hand thumb and the parts designated 25—25' constitute the left-hand thumb groove. Here again the positioning of the part 24' with relation to part 24 and the part 25' with relation to part 25 is such as to accommodate a comfortable or relaxed position of the thumbs when 45 in place in the grooves.

Fig. 4 discloses that the separate parts of each finger groove are so positioned that when a finger is extended for the purpose of being worked 50 on by the manicurist it engages only the portion of the groove adjacent the knuckle of the hand. That is to say, when the left hand is in position on the rest and the index finger is extended as shown in Figure 4, the finger engages 55 only the portion 20 of the rest and consequently the flexibility of both joints of the finger accommodates and assists the manicurist throughout such finger manipulations as may be necessary. The thumb grooves are correspondingly 60 formed and Figure 1 shows the position of the rest 7 with relation to the standard 6 when the thumb of the right hand is being worked upon by the manicurist; i. e., the thumb rests in the groove made up of the parts 24—24' and the 65 first joint of the thumb will engage the part 24 of the rest but the tip of the thumb will be lifted free of the portion 24' and held in such a position by the manicurist as it is being worked upon.

For the sake of lightness, the rest 7 is of shell-like form and the opening to the hollow interior is or may be partially surrounded by a downwardly extending flange 26 (Fig. 2) which may have formed therein the parts 20'', 21'', 22'' and 23'' of the finger grooves all as shown in Fig. 3, and the flange may be of such width that the extreme tips of the fingers will extend past it when lying in a relaxed position on the rest 7.

The bottom of the standard 6 is preferably 10 covered with felt for the purpose of deadening noise and also for the purpose of preventing the standard from marring the table or such other piece of furniture as may be employed as its support. It will also be understood that the adjustment of the rest 7 is essential to the proper functioning of the device and that the adjustment of the standard 6 with relation to the pedestal 5 also contributes to the comfort of both the operator and the subject. 20

While I have described but one embodiment of my invention it will be apparent that various changes, additions, and omissions may be made in the apparatus illustrated without departing from the spirit and scope of my invention as 25 defined by the appended claims.

Having thus described my invention, what I claim as new and desire to secure by Letters Patent is:

1. A manicurist's hand support comprising a 30 pedestal, a standard secured to the pedestal, a hand rest movably mounted on the standard and means for locking the hand rest in adjusted positions with relation to the standard.

2. A manicurist's hand support comprising a 35 pedestal, a standard secured to the pedestal, a hand rest comprising a shell-like portion having thumb and finger grooves formed therein movably secured to said standard.

3. A manicurist's hand support comprising a 40 pedestal, a standard secured to the pedestal, a bi-laterally symmetrical hand rest having four finger supporting grooves and two thumb supporting grooves formed therein, and means for adjustably securing said rest to said standard. 45

4. In a manicurist's hand support, a hand rest having finger grooves formed therein each consisting of three aligned and connecting grooves located at an angle to each other.

5. In a manicurist's hand support, a hand 50 rest having thumb and finger grooves formed therein each consisting of a plurality of hollowed, aligned sections lying at an angle to each other.

6. In a manicurist's hand support, a pedestal, a standard movably mounted thereon, a hand 55 rest movably mounted on the standard, means for locking the standard in adjusted position with relation to the pedestal and means for locking the rest in adjusted positions with relation to the standard.

7. A manicurist's hand support comprising a 60 supporting pedestal, a standard and a hand rest carried by the standard and movable to different positions with relation to said pedestal, and means for locking said hand rest in such 65 different positions.

FERNANDO PEREZ.
